US0D1008184S

(12) **United States Design Patent** (10) Patent No.: **US D1,008,184 S**
(45) Date of Patent: ** Dec. 19, 2023

(54) **CHARGER FOR WEARABLE ACTIVITY TRACKER**

(71) Applicant: **LG ELECTRONICS INC.**, Seoul (KR)

(72) Inventors: **Youngjoo Cho**, Seoul (KR); **Daekee Shin**, Seoul (KR)

(73) Assignee: **LG ELECTRONICS INC.**, Seoul (KR)

(**) Term: **15 Years**

(21) Appl. No.: **35/515,905**

(22) Filed: **Dec. 8, 2022**

(80) **Hague Agreement Data**

Int. Filing Date: **Dec. 8, 2022**

Int. Reg. No.: **DM/225731**

Int. Reg. Date: **Dec. 8, 2022**

Int. Reg. Pub. Date: **Dec. 30, 2022**

(30) **Foreign Application Priority Data**

Jul. 4, 2022 (KR) 30-2022-0026705

(57) **CLAIM**

The ornamental design for a charger for wearable activity tracker, as shown and described.

DESCRIPTION

1. Charger for wearable activity tracker

1.1 : Perspective

1.2 : Front

1.3 : Left

1.4 : Right

1.5 : Top

1.6 : Bottom

1.7 : Reference view

The broken lines shown in reproductions 1.1 to 1.6 depict portions of the charger for wearable activity tracker that form no part of the claimed design; a rear view is omitted because it is a mirror image of the front view; reproduction 1.7 shows a state of use at charging wherein the broken lines depict environmental structure that form no part of the claimed design.
